DESIGN FOR A FISHING ROD TIP

Julius M. Lonn, Aurora, Ill.

Application July 29, 1940, Serial No. 94,003

Term of patent 7 years

To all whom it may concern:

Be it known that I, Julius M. Lonn, a citizen of the United States of America, residing at Aurora, in the county of Kane and State of Illinois, have invented a new, original, and ornamental Design for a Fishing Rod Tip, of which the following is a specification, reference being had to the accompanying drawing, forming a part thereof, in which:

Fig. 1 is a view in side elevation of a fishing rod tip embodying my new design.

Fig. 2 is an edge elevational view thereof; and Fig. 3 is a top plan view.

What I claim is:

The ornamental design for a fishing rod tip, as shown.

JULIUS M. LONN.
